UNITED STATES PATENT OFFICE

2,588,301

CENTRIFUGAL SPEED CONTROL FOR
VACUUM CLEANERS

Leland H. Snyder, Chicago, Ill., assignor, by mesne assignments, to Knapp-Monarch Company, St. Louis, Mo., a corporation of Delaware

Application April 22, 1946, Serial No. 664,135

1 Claim. (Cl. 318—325)

1 This invention relates to a vacuum cleaner and particularly to a mechanism permitting selective manual variation of the intensity of the air current produced by the fan of the vacuum cleaner.

It has long been recognized in the art that some measure of speed control for the fan of a vacuum cleaner is most desirable, both in the operation of the vacuum cleaner as a rug cleaner or in the operation of the vacuum cleaner with the so-called vacuum attachments to provide a suction current of air for cleaning of upholstered furniture, drapes, Venetian blinds, etc. Obviously, for cleaning of rugs having a heavy nap it is desirable to utilize the maximum intensity of air stream which the fan and motor of the vacuum cleaner can develop; however, such maximum intensity air stream is much in excess of the desirable intensity when cleaning rugs having a shorter nap of floor rugs of the so-called "throw rug" variety. Likewise, when the cleaner is converted for use with vacuum attachments, the intensity of the suction air stream desired varies greatly with the use to which the cleaning attachments are put. A very strong intensity air stream might be desirable for cleaning radiators but would actually be harmful if applied to the cleaning of drapes or delicate curtains. While vacuum cleaners have heretofore been known in the art which incorporated a control circuit permitting the selection of two or three different speeds of operation, such arrangements utilize electrical interconnections of a plurality of windings of the motor, which had to be specially wound to permit such speed control to be obtained. Furthermore, the resulting electrical connections and switches required to effectuate speed control in such manner were complicated and expensive.

Accordingly, it is an object of this invention to provide an improved vacuum cleaner construction and particularly an improved speed control arrangement for the motor driven fan of a vacuum cleaner by which the intensity of air current produced by the fan may be conveniently manually adjusted over a wide range.

A further object of this invention is to provide an improved speed control for a motor driven fan of a vacuum cleaner incorporating a mechanically adjustable centrifugal switch which eliminates the necessity for special windings on the motor or complicated electrical switching arrangements to effectuate the speed control of the motor.

A particular object of this invention is to provide an improved variable speed control for a vacuum cleaner wherein the manual control knob is conveniently located at the end of the handle

2 of the vacuum cleaner and the mechanical connection between such control knob and the speed regulating mechanism is housed within the hollow handle.

The specific nature of the invention as well as other objects and advantages thereof will become apparent to those skilled in the art from the following detailed description of the annexed sheets of drawings which, by way of preferred example only, illustrate two specific embodiments of the invention.

On the drawings:

Figure 1 is an elevational view, partly in section, of a vacuum cleaner casing embodying a speed regulating device constructed in accordance with this invention.

Figure 2 is an elevational view of the centrifugally operated electric switch utilized in the construction of Figure 1;

Figure 3 is an electric circuit diagram showing the connection of the contacts of the centrifugal switch relative to the motor armature and winding;

Figure 4 is an elevational view of a modification of this invention wherein the manual control member for the speed adjusting mechanism is located on the handle;

Figure 5 is a partial sectional view of Figure 4 illustrating the speed regulating mechanism;

Figure 6 is a partial sectional view of the upper portion of the handle of the vacuum of Figure 4.

Figure 7 is a detail view, partially in section, showing the speed regulating mechanism of Figure 5.

35 As shown on the drawings:

Referring to Figure 1, there is shown a vacuum cleaner construction comprising a hollow casing 2 which is movably supported on a floor or rug surface by a plurality of wheels 4. Casing 2 is divided by a transverse partition 6 into a forward fan chamber 8 and a rearward motor chamber 10. A motor 12 is suitably mounted in motor chamber 10 and may comprise any conventional form of motor such as a so-called universal type commutator motor. Motor shaft 14 projects forwardly into fan chamber 8 and a suitable fan 16 is mounted thereon.

The structural details thus far described form no part of this invention and for description in greater detail, reference may be had to my co-pending joint application with Robert F. Lindgren, Serial No. 684,718, filed July 19, 1946, now abandoned. As is more fully described in my co-pending application, a suitable opening is provided in the front wall of fan chamber 8 to selec-

tively accommodate a hose coupling 18 by which the vacuum cleaner fan may be utilized to operate any one of a plurality of well known vacuum attachments. Of course, when the hose coupling 18 is removed from its connection with fan chamber 8 the air stream developed by fan 16 is drawn upwardly from the floor or rug immediately below the forward portion of the casing 2 in conventional manner. In either event, the intensity of the air stream produced by the fan 16 may be readily controlled by controlling the speed of rotation imparted to the fan 16 by the motor 12.

To accomplish a manual control of the speed of motor 12 a centrifugally operating electrical switch unit 20 is assembled to the rear end of the motor shaft 14. Centrifugal switch 20 may comprise any one of several well known forms of such switches which operate to open their contacts at a speed which is determined by the position of an adjusting member, but preferably the centrifugal switch unit 20 comprises a speed regulating unit similar to that shown and described in U. S. Patent No. 1,767,146, issued June 24, 1930, to Royal Lee. As is more fully described in the above referred to Lee patent, the centrifugal switch unit 20 comprises an insulating disk 32 upon which are mounted a pair of switch blades 22 each carrying switch contacts 24 which are arranged to separate at a predetermined rotational speed dependent upon the restraining force imparted to one of the switch blades by an adjusting member 26. Adjusting member 26 is pivoted to the disk 32 and provided with a ball-like portion 27 which is disposed substantially at the rotational axis of the centrifugal switch 20 and connected through a link connection 28 with one of the switch blades 22. Hence, a variation of the axial position of the ball portion 27 of the adjusting member 26 will produce a variation in the speed at which the contacts 24 of the centrifugal switch unit 20 open. On the other side of disk 32 a pair of slip rings 34 are provided by which electrical connections are made with the switch contacts 24 through the respective cooperation of a pair of brushes 35 with such slip rings.

While the specific wires accomplishing the electrical interconnection of the centrifugal switch 20 with the motor 12 are not shown in Figure 1, the electrical circuit is preferably arranged as shown in Figure 3. Thus the motor 12 is adapted to be connected to a source of power through a primary off-on switch 40 which may be located at any convenient place on the carpet sweeper and a series connection is effected between the field coils 42 of the motor, the armature 44 and the contacts 24 of switch 20. Preferably a resistor 46 and condenser 48 are connected in parallel to the contacts 24. It is therefore apparent that the opening of the contacts 24 produces a reduction in the voltage applied to the armature of motor 12 due to the voltage drop across resistor 46 and accordingly the speed of such motor is reduced to a point where the contacts 24 again close. Hence the speed of motor 12 and fan 16 is determined by the particular setting of the adjustable member 26 of the centrifugal switch unit 20.

In accordance with this invention, the adjustable member 26 is manually controlled from the exterior of the casing 2. In the modification illustrated in Figure 1, a bell crank lever 50 is medially pivoted on pin 52 on the inside of casing 2 and the one arm 54 of the lever 50 engages the adjustable member 26 to position such member at any one of a plurality of points along the axis of shaft 14. The other arm 56 of lever 50 is en-

gaged by a manually operable cam 58. Cam 58 comprises a disk-like member having an eccentric peripheral surface 60 and cam 58 is rigidly secured to a hub 62 which is rotatably journaled in the side wall of casing 2. Since the casing 2 is a relatively thin walled member, it is preferable to provide a hollow bushing 64 which has a head portion 66 complementarily shaped to conform to the exterior of casing 2 and a shank portion 68 which projects into the interior of casing 2 through a suitable aperture. Bushing 64 is secured to the side wall of casing 2 by any suitable means such for example as by the annular plate 70 and the screws 72. A manual operating knob 74 is secured to the outwardly projecting end of hub 62 and provides a convenient means by which the rotative position of cam 58 may be manually adjusted. Obviously, rotation of cam 58 produces a displacement of adjusting member 26 of the centrifugal switch unit 20 thereby controlling the speed of the motor 12 and fan 16.

Referring now to Figures 4 through 6, wherein identical numerals refer to similar parts as in the above described modification, a modification 25 of this invention is shown wherein the manually operable knob for adjusting the rotative position of the speed controlling cam 58 is mounted on the end of the hollow handle 76. Handle 76 is pivotally secured at its bottom portion to the 30 sweeper casing 2 in conventional manner. A motor 12, fan 16, centrifugal switch unit 20, lever 50 and speed controlling cam 58 are provided within the casing 2 and are identical with corresponding elements already described in connection with the modification of Figure 1.

The handle 76 comprises a hollow tubular member which extends from the casing 2 in a generally upstanding direction and in the upper end of handle 76 a manual control knob 78 is 40 rotatably journaled on an integral hub portion 80. Control knob 78 is secured in assembled relationship to the handle 76 by means of a spring ring 82 which in the assembled position, lies partly in an annular exterior groove 84 provided 45 on the hub portion 80 of operating knob 78 and an annular interior groove 85 provided in the handle 76.

To effect a driving connection between operating knob 78 and the hub 62 upon which speed 50 adjusting cam 58 is mounted, a mechanical connection is provided between hub 62 and operating knob 78 which preferably comprises a flexible shaft element 86. Flexible shaft 86 is disposed throughout the major portion of its length 55 within the bore of the hollow handle 76 and at its upper end projects into a suitable axial recess 88 in the operating knob 78 and is rigidly secured therein by a set screw 90. At its lower end, flexible shaft 86 projects out of a suitable aperture (not shown) in the side wall of handle 76 and is inserted in an axial opening 92 provided in the hub 62. The inserted end of flexible shaft 86 is rigidly secured to hub 62 by a set screw 94 which 60 also secures a ring element 96 to the hub 62 to prevent axial displacement of the hub 62 and cam 58 relative to the bushing 64 in which the hub 62 is rotatably journaled.

The operation of this modification is identical to that already described in connection with the modification of Figure 1. The operator need only rotate the operating knob 78 to produce a desired variation in the speed of the motor 12 and fan 16 to adjust the intensity of the air current produced by the fan 16 to that value which is

most suitable for the particular cleaning operation being accomplished.

It will, of course, be understood that various details of construction may be varied through a wide range without departing from the principles of this invention and it is, therefore, not the purpose to limit the patent granted hereon otherwise than necessitated by the scope of the appended claim.

I claim as my invention:

In a vacuum cleaner, a casing, a fan in said casing, a motor in said casing driving said fan, a hollow upstanding handle connected to said casing, said fan being rigidly attached to the rotatable shaft of said motor, a centrifugally operated electric switch driven by said motor, an adjusting member on said switch axially movable to adjust the speed at which said centrifugal switch opens, means connecting said switch in the energization circuit of said motor, whereby the opening of said switch reduces the speed of said motor, cam means rotatably journalled in said casing and adjustably engageable with said adjusting member axially to control the speed

of said motor, a manually operable control knob rotatably journalled on said handle, and a flexible shaft disposed in said hollow handle and connecting said knob and said cam means, whereby manual rotation of said knob rotates said shaft and said cam means to selectively vary the intensity of the air current produced by said fan.
